UNITED STATES PATENT OFFICE.

REUBEN B. BENJAMIN, OF CHICAGO, ILLINOIS, ASSIGNEE TO BENJAMIN ELECTRIC
MANUFACTURING COMPANY, OF CHICAGO, ILLINOIS, A CORPORATION OF ILLINOIS.

CLUSTER LAMP-SOCKET.

946,892.

Specification of Letters Patent. Patented Jan. 18, 1910.

Application filed November 29, 1907. Serial No. 404,421.

To all whom it may concern:

Be it known that I, REUBEN B. BENJAMIN, a citizen of the United States, residing at Chicago, in the county of Cook and State of Illinois, have invented new and useful Improvements in Cluster Lamp-Sockets, of which the following is a full, clear, concise, and exact description, reference being had to the accompanying drawing, forming a part 10 of this specification.

This invention relates to improvements in cluster lamp sockets, and has special reference to switching means for controlling the lamps carried by the device.

15 The principal object of the invention is the provision of a device of this class having improved means carried by and forming a part of itself, and readily operated, for lighting or extinguishing the lamps. In the accomplishment of this object I preferably locate the switch mechanism within the body of the device itself, and provide means whereby this switch mechanism may be operated by a pull imparted to a cord, chain or equivalent device. The cord, chain or the like may, and usually will, depend from the lower portion 25 of the cluster so that it may be readily grasped and pulled to switch the lamps into or out of circuit.

30 In the accompanying drawings, Figure 1 is a view of the assembled device, part of the casing being broken away to expose to view the switching mechanism, the latter being shown in section; Fig. 2 is a top plan view of 35 the hollow insulating base and the switching mechanism contained therein; Fig. 3 is a cross sectional view of the same on the line 3—3 of Fig. 2, in a plane at right angles with the plane of Fig. 1; Fig. 4 is a bottom 40 plan view of the base; Fig. 5 is a perspective view of a contact ring with which the center terminals of the lamps engage when inserted into the sockets of the device; Fig. 6 is a perspective view of a portion of the upper 45 edge of the hollow base, showing the means by which this base is supported in place; Fig. 6^a is an elevational view of a supporting cap to which the base is removably secured; Fig. 7 is a detail sectional view showing the 50 means whereby the contact ring shown in Fig. 5 is secured to the base, the section being taken on the line 7—7 of Fig. 2; Fig. 8 is a sectional view showing a portion of the 55 switching mechanism, the section being taken

on the line 8—8 of Fig. 1. Figs. 9 and 10 55 are perspective views of two members which when placed together form a pulley to which is secured the actuating cord or chain; Fig. 11 is a perspective view of the frame which carries the moving parts of the switch; Fig. 60 12 is a perspective view of a plate which carries one of the switch contacts; Fig. 13 is a perspective view of an eccentric follower employed in the switching mechanism; and Fig. 14 is a perspective view of a portion of a ring 65 plate which occupies the upper portion of the casing and engages suitable means on the supporting cap, whereby the casing is sustained in place.

In the several figures of the drawings, 70 in which like reference numerals indicate the same parts throughout, 15 is a supporting cap which corresponds to the usual back plate in devices of this class, and which is secured to the ceiling or to the lower end 75 of a pipe or similar conduit and carries the other parts of the device. This cap has the general form of an inverted cup and is formed of sheet metal. The insulating base 16 is of general inverted-cone shape, its 80 upper and larger portion being inserted into the cap 15 and sustained therein by means of lugs 17, preferably three in number, spaced around the edge of the base 16. These lugs rest upon inwardly projecting 85 ribs 18 in the cap 15. These ribs 18 are three in number and are elongated as shown in Fig. 6^a and are provided with upwardly extending stop portions 19. When the base 16 is to be secured in place in the cap 15 90 the base is put up into place in the cap with the three lugs 17 passed up through the spaces between the inwardly projecting ribs. These spaces are indicated 20 in Fig. 6^a. These lugs having passed up between the 95 ribs 18, the base will then be rotated to carry the lugs around over the ribs 18 into the position indicated in dotted lines in Fig. 6^a, in which position these lugs will engage the upwardly extending stops 19 and the base 100 will be held against further rotation in the cap.

The base 16 is hollow, and located in the chamber therein is the switching mechanism to be hereinafter described. This base has 105 an opening 21 in the bottom thereof through which extends a cord, chain or the like for operating the switch. The outer casing or

body 22 consists of a substantially hemispherical shell and is provided with the bead 22^a in which is disposed an annular plate 23 provided with three inwardly projecting lugs 24. As the ribs 18 in the cap 15 are formed by pressing the material of the cap inwardly, these ribs 18 appear upon the exterior of the cap as depressions or grooves, and into these depressions extend 10 the lugs 24 on the ring 23 when the casing is in place. In securing the casing to the cap the casing is placed in such a position that the lugs 24 on the ring 23 may slip up into the downwardly extending and widened 15 portion 25 which leads into the depression 18, and after the casing has been thrust up as far as possible it is then given a slight turn in a right hand direction, whereupon the lugs 24 pass around into the grooves 18. 20 To prevent backward rotation of the casing and consequent detachment of the casing from the cap, each of the lugs 24 is provided with a leaf spring 26 which is secured in place on the ring 23 over the lug and 25 bears against the upper edge of the groove. The casing 22 carries the lamp-holding sockets 27, these sockets being insulated from the casing by insulating rings 28 and connected with a metallic ring 29 which has 30 a number of downwardly extending resilient lugs 30. When the casing is put up into place these lugs 30 engage a dished plate 31 which is secured upon the lower side of the base by means of screws 32, 32 passing 35 through inturned lugs 33, 33 on this dished plate. These screws and the plate 31 are electrically connected with one of the terminals of the switch, as hereinafter explained, the other terminal of the switch being connected 40 to one of the leads so that when the switch blades are in the "on" position, electrical connection is made between this lead and the plate 31, and consequently between the lead and the sockets 27. To prevent the 45 base 16 from sliding upward in the cap 15 when the casing is put up into place the cap is provided with downwardly and inwardly extending fingers 15^a against which the upper side of the base rests. These fingers 50 may be formed of the sheet metal of the cap, as shown in Fig. 1.

The center terminals of the lamps engage a ring contact 34 which extends around the base 16 and is provided with a pair of lugs 55 35, 35 which extend inwardly and then upwardly through suitable openings in the base, as best shown in Fig. 7. The upper end of each lug 35 is then bent over so as to rest upon a suitable shoulder 36 on the base, 60 whereby the ring contact 34 is securely held in place on the base without the use of screws, bolts or other separate fastening means. This ring 34 is also provided with an inwardly extending lug 37 carrying a 65 binding-screw 38. The base is formed with

an opening 39 through which a lead may be brought and secured to the binding screw 38, electrical connection being thus established between this lead and the center terminals of the lamps. It will be seen that the binding-screws and switch mechanism are carried by the base, while the lamp-holders are carried by the casing. When the casing is put up into position one of the terminals of each of the lamps is brought into electrical communication with one of the leads and the other terminal of each lamp is electrically connected with one side of the switch. The other side of the switch being connected with the other lead, the circuit is completed through the switch and lamps when the switch is in the "on" position. A casing containing a different number of lamps may be readily substituted without disturbing the base or switch mechanism. 70 75 80 85 90 95 100 105 110 115 120 125 130

The movable parts of the switch are supported by a frame 40, shown in perspective in Fig. 11, this frame being secured in place in the chamber within the base by the screws 32, 32 and being thereby electrically connected with the plate 31 which, as above explained, is in electrical communication with the outer contacts of the lamps when the casing is in place. This frame 40 has bearings 41 and 42 for the ends of the spindle or stem 43 of the rotary switch mechanism. Surrounding one end of this stem is a spring 44 secured at one of its ends to the frame 40 in any convenient manner and having its opposite end secured to a pulley 45 loosely mounted on the shaft 43. This pulley 45 is conveniently formed of the two sheet metal members 46 and 47 shown in perspective in Figs. 9 and 10. The portion 46 consists of a disk while the portion 47 comprises a cup-shaped shell having an annular flange 48 and provided with a pair of projecting tongues 49, 49, entering corresponding apertures 50, 50 in the disk 46. These projections 49 may be bent over upon the plate 46 to secure the members 46 and 47 together. To the pulley 45 thus formed is secured one end of a cord 51, or, if preferred, a chain, extending downwardly through the central opening in the bottom of the base and through a suitable opening 52 in the casing of the device. A ratchet connection is provided between the shaft 43 and pulley 45, whereby when the pulley is rotated in one direction under the influence of the spring 44 the pulley may turn freely on the shaft, but when the pulley is rotated in the opposite direction by a pull exerted upon the cord, with the consequent unwinding of the cord from the pulley, the shaft will be locked to the pulley and will be turned therewith. This ratchet connection is provided by cutting the disk 46 as illustrated in Fig. 9 and turning the tongues 53, 53 thus formed backwardly so as to form resilient spring pawls, and by providing

upon the shaft 43 a toothed disk 54 fast on said shaft and disposed so that it will be engaged by these pawls. When the pulley is rotated in one direction by the spring 44 the 5 pawls will pass over the teeth of the disk; when the pulley is rotated in the opposite direction by the unwinding of the cord when pulled upon these teeth will be engaged by the pawls and the shaft will turn with the 10 pulley. The method which I employ for securing the disk 54 on the shaft 43 consists in flattening the shaft at the point where it is surrounded by the disk and slipping over this flattened portion a U-shaped clip 55, and 15 providing the plate 54 with an opening of the same form as the outer contour of the clip so that the clip and the disk are compelled to rotate together.

The switch mechanism which is mounted 20 upon the shaft 43 may be of any approved form, preferably of the snap type, and I have illustrated a well known and extensively used form of such switch mechanism. This mechanism comprises a pair of stationary contacts and a rotary switch blade 25 adapted to engage and bridge these contacts when in the "on" position and to be turned out of engagement therewith when the circuit is to be broken. The stationary 30 contact 56 is carried by the frame 40 of the switch mechanism, while the other stationary contact 57 is insulated from the frame, being carried by a plate 58 (shown in perspective in Fig. 12). This plate is secured 35 in position by screws 59 and 60, the screw 60 extending into a plate 61 which is arranged upon the under side of the base and carries a binding screw 62. An opening 63 in the base affords a passage through which 40 a lead may be brought to the binding screw. When the blade 65 is in the "on" position current is conducted from the contact 57 through the blade to the contact 56, thence 45 through the frame 40 and the screws 32, 32 to the plate 31 and the outer contacts of the sockets.

The blade 65 is secured to a barrel 66 which turns on the shaft. In the barrel 66 is arranged a spring 67 having one of its 50 ends secured to the shaft 43 and its opposite end secured to the barrel, whereby when the shaft 43 is revolved by pulling down the cord this spring 67 is placed under increased tension and tends to revolve the switch 55 blade. Secured to the shaft and revolving therewith is an eccentric 68 surrounded by a plate (shown by itself in Fig. 13) comprising an annular portion 69 surrounding the eccentric and a projection 70 extending 60 therefrom which normally engages one of four lugs 71 on the frame 40. Lying between the eccentric and the switch blade, and turning with the blade, is a plate 72, this plate being provided with a projection 65 73 which normally engages the projection 70

on the ring 69. The spring 67 tends at all times to revolve the blade 65 and plate 72, but these parts are held against rotation by the projection 70 on the ring 69, which projection is confined between the lug 71 on the frame and the projection 73 on the plate 72. When the shaft is revolved by pulling on the cord, the spring 67 is placed under increased strain and at the same time the eccentric is turned in the ring 69. When the 75 shaft has made one-fourth of a revolution, the blade is released by the projection 70 on the ring 69 being drawn inwardly sufficiently to permit it to pass under the lug 71. When thus released the blade suddenly turns 80 through one-fourth of a revolution. This revolution of the blade about the shaft carries the ring 69 around on the eccentric, thereby causing the projection 70 to move outwardly into engagement with the next 85 succeeding lug 71. By this means the blade is held back while the shaft is being turned through a quarter of a revolution and is then suddenly released, whereby connection is quickly made or broken between this 90 blade and the stationary contacts with which it co-operates. When the blade is in a horizontal position it electrically connects the stationary contacts with each other, and when it has turned to an upright position 95 the connections are broken and the switch is in the "off" position.

I have illustrated my device as being provided with a well known form of rotary snap switch mechanism, and for the purpose of making this specification clearer have described such a mechanism, but desire it to be understood that my invention comprises the use of any form of switch mechanism which may be adapted to be mounted 100 within the body portion of a plural lamp-holding device and to be actuated by pull-operated mechanism.

Having thus described my invention, what I claim as new and desire to secure by Letters Patent is:

1. A cluster lamp socket, comprising in combination a hollow insulating member provided with an opening in its under side, switching means within said member, contacts without said member, means inclosing said insulating member and provided with lamp-receiving openings, means for sustaining lamps in said openings in position to engage said contacts, and flexible means extending outside said inclosing means for operating said switching means by a pull exerted upon said switching means.

2. In a cluster lamp socket, a supporting cap, an insulating base detachably secured 125 to said cap and formed with a chamber and having an opening into said chamber in the under side thereof, a body detachably secured to said cap and carrying the lamps and inclosing said base, switch mechanism 130

- in the chamber of said base, pull-operated means extending through said opening for actuating said switch mechanism, and means for making electrical connection between the 5 lamps and said switch mechanism when the body is put into position.
3. In a cluster lamp socket, a supporting cap, an insulating base detachably carried thereby, a body detachably secured to said 10 cap and carrying the lamps, switch mechanism supported by said base, means for connecting the lamps with said switch mechanism when the body is in position, and means extending to the exterior of said body for 15 operating said switch mechanism.
4. In a cluster lamp socket, a supporting member, an insulating base carried by said member, a body supported by said member and removable independently of said base, 20 said body being arranged to carry the lamps, switch mechanism supported by said base, means for making electrical connection between the lamps and said switch mechanism when the body is in position, and means extending to the exterior of said body for operating 25 said switch mechanism.
5. In a cluster lamp socket, an insulating member having a chamber therein and carrying lamp-engaging contacts, rotary snap 30 switch mechanism disposed in said chamber and having the axis of its rotary part extending across said chamber, and pull actuated means extending to the exterior of the device for operating said switching mechanism.
6. In a cluster lamp socket, an insulating base, a body surrounding said base, means for sustaining said body and base and permitting the removal of either of said parts independently of the other, switch mechanism carried 40 by said base, lamp-holders carried by said body, and means extending to the exterior of said body for operating said switch mechanism.
- 45 7. A cluster lamp socket comprising a circular body formed with openings for the reception of lamps, means for supporting a plurality of lamps in said openings, contacts within said body for engaging the terminals of said lamps, switching mechanism within said body for controlling said lamps, said switching mechanism comprising a circuit-completing member arranged to revolve on an axis perpendicular to the axis of said
- body, and means extending outside said body 55 for actuating said switching mechanism.
8. In an incandescent lamp cluster, in combination, a block having a central contact chamber, a socket frame mounted on said block and having a plurality of sockets for 60 lamps, a key rotatably mounted in said chamber, contacts projecting into said chamber and leading current to the lamps, said key having a segment with notches in the periphery thereof, and a spring engaging 65 said segment and holding said key in different positions.
9. In a cluster lamp socket, an insulating base having a chamber therein, switch mechanism within said chamber, a body surrounding 70 said base and arranged to carry the lamps, snap switch mechanism within said chamber, flexible means extending from said chamber for operating said switch mechanism, and means for making electrical connection 75 between said switch mechanism and the lamps when the body is in position.
10. In a cluster socket, the combination of a body arranged to carry the lamps, a hollow base insertible thereinto and provided 80 with an aperture, binding terminals carried by said base for the attachment of leads, switch mechanism within said base, means for making electrical connection between said switch mechanism and said lamps when 85 said base is in position in said body, said body having an opening opposite the aperture of the base, and means extending through said opening and aperture into the chamber in said base, for operating said 90 switch mechanism.
11. In a cluster lamp socket, a body arranged to carry the lamps, a base removable from said body, switch mechanism carried by said base, means for operating said switch 95 mechanism, said body having an opening for the passage of said switch-operating means, and interengaging means for electrically connecting the lamps with said switch mechanism when the base is placed within said 100 body.

In witness whereof, I have hereunto subscribed my name in the presence of two witnesses.

REUBEN B. BENJAMIN.
